UNITED STATES PATENT OFFICE.

CORNEL RIDDERHOF, OF NEW YORK, N. Y.

TOY.

Application filed July 29, 1922. Serial No. 573,480.

To all whom it may concern:

Be it known that I, CORNEIL RIDDERHOF, a citizen of the United States, and a resident of New York, in the county of New York and State of New York, have invented a new and Improved Toy, of which the following is a full, clear, and exact description.

This invention relates to improvements in toys and more particularly to what I term a ball car, an object of the invention being to provide a toy having a body, frame, or member which constitutes in effect a vehicle and in which a propelling ball or sphere is located, which when drawn over the floor will 10 act as a propelling device by reason of momentum stored in the ball, and will provide an improved means whereby the body or rather brake members carried by the body, will check the momentum of the ball when 15 the body is caused to assume an angular position from normal.

A further object is to provide a toy of the character stated which not only gives entertainment and amusement, but enables the 20 operator to exercise skill in manipulating the toy.

With these and other objects in view, the invention consists in certain novel features of construction and combinations, and arrangement of parts, as will be more fully hereinafter described and pointed out in the 25 claims.

In the accompanying drawings—

Figure 1 is a view in side elevation illustrating one embodiment of my improved toy.

Figure 2 is a view in longitudinal section showing the position of the ball by dot and dash lines.

Figure 3 is a view of the body with the ball removed.

1 represents a movable body which is of general cylindrical shape having an enlarged annularly extended base 2 resting on the floor and provided with an annular external bead 3 at its upper edge. The body 1 is formed with inwardly projecting curved brake shoes 4 which may be formed by bending the metal of the body inwardly by an ordinary stamping operation, as indicated in the drawings, but my invention is not limited to particular manner of forming the brake shoes.

5 represents a relatively heavy ball or sphere, which is located in the body and of slightly less diameter than the body, so that

the ball normally rests upon the floor and is normally spaced from the brake shoes 4.

A cord 6 is connected to the body 1 preferably by tying the same around the body under the bead 3, but it is obvious that the invention is not limited to any particular manner of attaching the cord, or other flexible device 6.

In operation the toy is caused to move over the floor or other surface by exerting a pull on the cord 6 and as said toy moves over the surface the frictional contact of the ball 5 with said surface will cause the latter to roll, and by reason of its weight will store 70 momentum and serve as a propelling means for the body when the pull on the cord ceases.

To check the momentum, it is simply necessary to exert a pull on the cord at an angle to the normal pull, or rather to exert a pull more toward the vertical as indicated in dash lines in Figure 1 to cause a tilting of the body 1 and to bring the brake shoes 4 into contact with the surface of the ball 5 to check the movement of the latter. By reason of this construction, the toy is under the control of the operator and he can cause the toy to move either by direct action of the cord, or by the momentum of the ball, 80 and he can check such momentum by giving a different angular pull to the cord so that in causing the toy to move from one place to another he can exercise a certain amount of skill in the manipulation of the toy. In 90 other words, the operator has complete control over the motion of the toy by simply changing the angle of the pull of the string toward the vertical; as for example, a slightly upward pull will serve to check the 95 movement of the toy by reason of the friction of the brake shoes 4 against the same.

In the particular toy illustrated no "sense" of direction is given, as the ball may turn freely in any direction, hence the operator 100 can race the toy into a corner and stop it by the brake action and draw it in another direction without turning, and to permit this it is necessary that the cord 6 shall fit loosely around the body, which is a preferred arrangement.

It is obvious that my invention is applicable to any form of body which either has, or has not a fixed direction of motion, and hence I do not wish to limit myself to the 110 particular shape of body indicated but desire to cover broadly the idea of the pro-

elling ball with means whereby the motion of the ball is checked when the angular disposition of the body is changed by the cord or other similar device.

5 Various slight changes might be made in the general form and arrangement of parts described without departing from my invention, and hence I do not limit myself to the precise details set forth, but consider 10 myself at liberty to make such changes and alterations as fairly fall within the spirit and scope of the appended claims.

I claim:

1. A toy of the character described, comprising a body, a propelling ball in the body and adapted to engage the surface over which it is moved, a flexible member attached to the body for moving it and imparting momentum to the ball to cause it 20 to propel the body when the pull on the member is released, and means for checking the momentum of the ball when the body is tilted.

2. A toy of the character described, comprising a body adapted to be moved over a surface, a propelling ball loosely fitting within the body engaging the surface over which the body is moved, and brake shoes in the body engaging the ball when the body 30 is tilted.

3. A toy of the character described, comprising a cylindrical body, a base on the body adapted to support the same, a ball

loosely fitting the body and resting upon the surface supporting the base, and brake 35 shoes projected inwardly from the body and adapted to engage the ball when the body is tilted.

4. A toy of the character described, comprising a cylindrical body, a base on the 40 body adapted to support the same, a ball loosely fitting the body and resting upon the surface supporting the base, brake shoes projecting inwardly from the body and adapted to engage the ball when the body 45 is tilted, a flexible body propelling device loosely secured around the body whereby the body can turn independently of the flexible device.

5. A toy of the character stated, comprising a cylindrical body, a base on the body, an external bead on the body, a ball loosely housed in the body, brake shoes in the body normally spaced from the ball, and a flexible device loosely secured around the 55 body and under the bead.

6. A toy of the character stated, comprising a spherical rolling member, a cylindrical body in which the said member is located, a flexible device secured to the body, 60 and means in the body for checking the movement of the member by a change in the pull on the flexible device in an upward direction.

CORNEIL RIDDERHOF.
